MAIL BAG.

No. 323,194.

Patented July 28, 1885.

UNITED STATES PATENT OFFICE.

ANDREW J. MORRISON, OF WEST TROY, NEW YORK, ASSIGNOR OF ONE-HALF TO JOHN N. BAXTER, OF RUTLAND, VERMONT.

MAIL-BAG.

SPECIFICATION forming part of Letters Patent No. 323,194, dated July 28, 1885.

Application filed November 25, 1884. (No model.)

To all whom it may concern:

Be it known that I, ANDREW J. MORRISON, of West Troy, in the county of Albany and State of New York, have invented a new and 5 useful Improvement in Mail-Bags; and I do hereby declare that the following is a full, clear, and exact description of the same.

My invention relates to mail-bags, and includes special devices for forming the mouth 10 of the bag and securing said mouth, a reversible tag-holder, and devices for strengthening the bag and protecting it from wear, and also the application of leather handles to opposite sides of the bag near the bottom, to assist in 15 dumping contents.

In the accompanying drawings, Figure 1 represents, in front view, the upper and lower portions of the bag, the reversible tag-holder being in place and the flap being partly 20 broken away. Fig. 2 is a section on line *x x* of Fig. 1, showing the bolt-strap, the staples, the flap, and also the tag-holder in section. Fig. 3 is a section of Fig. 1 on line *y y*. Fig. 4 is a section of Fig. 1 on line *z z*. Fig. 5 is a 25 detail view, showing the tag-holder thrown back, and the handle portion of the bolt-strap. Fig. 6 is a plan view of the bottom of the bag. Fig. 7 is a section on line *q q*, Fig. 1.

I use the old and well-known general principle of fastening the mouth of the bag, the main features of which are the staples and sliding tongues.

In connection with this old and effective mode of fastening I have devised means for 35 preserving the flexibility of the bag across the mouth, for covering the ends of the staples, and for convenience and security in the locking. I have also improved the construction 40 of the bag by forming the body of the bag of canvas and the mouth of leather, suitably reinforced.

The front of the mouth of the bag is shown at A. It is provided with staples *a b*, securely riveted thereto. The staples *a* are set 45 in planes parallel with the sides of the bag, and are adapted to enter corresponding slits in the flap. The staple *b* is fitted to the locking-plate hereinafter described. The flap is formed of one or more thicknesses, and is folded over upon itself, the folded edge being shown at *c* and the fastened edge at *d*, this be-

ing the inner edge, and held by rivets. In the inner part of the folded flap are slots *e*, metal bound and adapted to receive the staples *a*. The fold made by the turned-down 55 edge of the flap being fastened at the edge only, as described, forms a sheath for the locking or bolt strap *G*. This is of leather or other flexible material, and is made longer than the width of the bag. It is provided with 60 slots *m*, which extend longitudinally of the strap, and as the strap is drawn back and forth these slots cross the metal-bound slots *e*. The bolts *g* are fixed by one end to the strap at one end of the slots, and project inwardly 65 over the slots in line with the staples *a*.

The special feature of the strap is that it is arranged to be unlocked by drawing from the middle inwardly to the center, and locked by drawing both ends outward from the center. 70

When the bag is to be locked, the ends 1 of the locking-strap are drawn outwardly, as represented in Fig. 4, and this draws the 75 bolts through the staples. The center of the strap is brought through slits in the fold of the flap and exposed on the surface for a space equal to the width of the locking-plate. It has a hole, 2, which fits over staple *b* when the 80 ends are drawn out and the central exposed part lies flat. The locking-plate *H* fits over the exposed portion of the strap and holds down this part, and is itself held by a padlock in the staple *b*. The plate *H* is hinged on the flap. This secures the center and renders it impossible to pull upon the center to 85 unlock the bag. In addition to this obstruction in the center, the strap is not sufficiently rigid to allow the projecting ends to be pushed back. This construction leaves the whole mouth of the bag flexible, and as the staples 90 extend through only one fold of the flap, their ends are covered by the other side and are concealed.

The operation of unlocking is very simple. The padlock is first removed, the locking- 95 plate is turned back, and then the center of the strap is drawn out and the ends both pulled in, this drawing all the bolts from the staples *a*.

A single thickness of leather forms the main 100 part of the bag-mouth. This is joined to the canvas of which the bag is made by a lap-joint,

and a strip, *h*, is lapped on the other side of the canvas and upon the leather of the main part. Thus the edge of the canvas is completely covered.

5 The body of the bag is of inexpensive material, sufficiently durable for that part, while the mouth only and the re-enforcements are formed of leather.

In the locking-plate *H* is a tag or card holder, *k*. This is either a plate adapted to be marked, or a frame adapted to hold a card or tag, and it is pivoted on end pins in an opening in the plate *H*. On these pins it may be turned over to expose one side or the other, according to the direction in which the bag is to be sent. For example, on one side of the tag may be the words "Rutland & Troy R. P. O. From Rutland, Vt.," and on the other "Rutland, Vt. From Rutland & Troy R. P. O."

10 When the bag is sent from Rutland, Vt., for example, the tag-holder is turned (while the plate *H* is raised) with that side of the card uppermost which has on it the legend "From Rutland." When the plate *H* is locked down 15 the tag-plate *k* is also held from turning. It is set properly when the mail-bag is closed for sending, and so remains until after the bag has been opened and is prepared for its return.

15 The bottom of the bag is formed of a piece, *l*, set in, and it is re-enforced by straps, one of which, *I*, runs lengthwise of the bottom, and has branches 5 5 over the corners of the bag. The straps *K* extend across the bottom, and are attached to the bottom through 20 the straps *I*. The ends of all of the straps are drawn up on the sides of the bag, as shown at 6. These ends are re-enforced by iron plates *7*, which are shod with small rods or bars *8*, fixed to the re-enforcing-plates. I 25 prefer to fix them to the plates by passing the upper ends of the rods (bent at right angles) through the plates and heading them down on the inside. The lower ends of the side bars, *8*, are bent around the ends of the plates 30 *7*, and serve to form bearings for the bag when it is drawn or dragged over the floor. The rods also serve as bearings their entire length. The parts are all securely held together by ordinary rivets. On each side, near the bottom, 35 I have provided handles *9*, of leather or other

suitable material, useful in clearing the bag of matter sometimes liable to lodge.

It will of course be understood that my invention may also be applied to leather bags, or bags of any other material.

55

I claim as my invention—

1. In combination with a bag and flap having its edge folded upon itself to form a sheath, the strap having locking-bolts contained within said sheath, and slots in the inner part of 60 said sheath to receive the staples, all substantially as described.

2. In combination, a flap of a bag having slots to receive the staples on the mouth of the bag, a locking-strap inclosed in a sheath in 65 the flap and exposed at its middle part, said strap having slots and bolts adapted to lock in the staples when the strap is drawn outward from the center, and a locking-plate adapted to cover the exposed portion of the 70 strap, all substantially as described.

3. In combination with the flap of the mail-bag having slots to receive the staples on the mouth of the bag, a locking-strap inclosed in the sheath in the flap and exposed at its middle part, said strap having slots and bolts adapted to lock in the staples when the strap is drawn outward from the center, a locking-plate adapted to cover the exposed portion of 75 the strap, and a label-holder pivoted in the 80 center of the said plate over the strap, as described.

4. In combination with the bottom of a mail-bag, the re-enforcing leather strips *K* and branches 5 5, and the metal side plates, *7*, substantially as described.

5. In combination with the bottom of a mail-bag, the re-enforcing leather strips *K* and branches 5 5, the metal side plates, *7*, and the rods *8*, fitted to said side plates and bent 90 around the bottom thereof, substantially as described.

In testimony whereof I have signed my name to this specification in the presence of two subscribing witnesses.

ANDREW J. MORRISON.
